SOLDER EXTRACTOR

William Jordan Siegel, 9337 Fraser St.,
Silver Spring, Md. 20910

Filed May 28, 1968, Ser. No. 12,105

Term of patent 14 years

Int. Cl. D8—02

U.S. Cl. D8—30

FIG. 1 is a top plan view of a solder extractor showing my design;

FIG. 2 is a left side view thereof;

FIG. 3 is a bottom view thereof;

FIG. 4 is a fragmentary view of the right side thereof;

FIG. 5 is a front view thereof; and

FIG. 6 is a rear view thereof.

I claim:

The ornamental design for a solder extractor, as shown and described.
